UNITED STATES PATENT OFFICE.

JAMES F. McELROY, OF LANSING, MICHIGAN, ASSIGNOR OF ONE HALF TO
LEWIS C. BUTLER, OF SAME PLACE.

SYSTEM OF ELECTRIC DISTRIBUTION.

SPECIFICATION forming part of Letters Patent No. 366,124, dated July 5, 1887.

Application filed February 3, 1887. Serial No. 296,383. (No model.)

To all whom it may concern:

Be it known that I, JAMES F. McELROY, of Lansing, in the county of Ingham and State of Michigan, have invented new and useful Improvements in Systems of Electric Distribution; and I do hereby declare that the following is a full, clear, and exact description thereof, reference being had to the accompanying drawings, which form a part of this specification.

1c This invention relates to a new and useful improvement for a system of electrical distribution for lighting; and the invention consists in the novel manner of arranging the local lamp-circuits so that a lamp (or group of lamps) is controlled by two manual switches—one near the lamp itself, as in the ordinary manner, and one at a more distant station—all in the manner and for the purpose hereinafter explained.

In the drawings which accompany this specification, Figure 1 is a diagram of my improved system. Fig. 2 is a plan of the switch, and Fig. 3 is a central section thereof.

A represents the positive and B the negative main conductors of an electrical supply. 20 C is a lamp (or group of lamps) located in the room or station D.

E F are positive and negative service-conductors for the lamp C, and E' F' are duplicate positive and negative service-conductors 30 for the same lamp, but in a room or station, S, distant from the lamp C.

I is the lamp-circuit arranged between the two stations, and G and H are two manual switches—one in the room D and the other at 35 the distant station S. Each of these switches has two fixed contacts, which are the terminals of the respective service-conductors, and one movable contact formed by the respective terminal of the lamp-circuit, all so arranged that 40 by placing the movable contact of either switch in electrical connection with either the positive or negative service-conductor the light may be turned on or off at will. The switches should be so constructed that the movable 45 contact is always electrically connected with one of the two fixed contacts, and in Figs. 2 and 3 such a switch is shown in detail, and is arranged as follows: An insulating-case, a, is provided with a central spindle, b, suitably 50 journaled therein. This spindle carries a suitable button, c, for turning it by hand, and has

secured to it the metallic spring d. The inner walls of the case around the spindle are formed in two cylindrical halves; but each half is eccentrically disposed to the other and 55 to the spindle, so as to be separated by radial offsets or shoulders m m. The upper portions of each of these cylindrical halves is provided with a metallic lining, e, electrically disconnected from each other and provided with top 60 flanges, h, to which the terminals of the positive and negative service-conductors are respectively secured. The lower portion of each of these cylindrical halves is similarly provided with a metallic lining, f, electrically disconnected from the metallic linings e, but electrically connected with each other by the bottom lining, g, to which the terminal of the lamp-circuit is secured. The spring d in any of its 65 positions is always in electrical contact with one of the upper and one of the lower metallic linings, e f, and thus the lamp-circuit is always in electrical connection with one of its service-conductors. If the spindle b is turned to the right, a click of the spring d tells the operator 70 that the lamp-connection is changed from one service-conductor to the other. The offsets m also prevent the short-circuiting of the service-conductors.

The advantage of my improved system may 75 be best illustrated by a special application thereof. Suppose the station D represents the office-room and the station S the residence of the executive officer of an institution provided with an electric-light plant. It will be seen 80 that if the installation is made on the plan described the officer will be able to turn on the light in his office from his residence, and thus be saved the inconvenience of entering the dark office, and upon leaving his office he can 85 turn off the light without going back to his residence. If the lamp at his residence is in a similar circuit, he can turn on the lamp at his residence when he wants to repair thereto from his office. It will be seen that this system of 90 electrical distribution may be applied to other translating devices where it is desirable to obtain similar advantages of control from two stations.

What I claim as my invention is—

1. The combination of a local lamp circuit having one of its terminals at the local station

and the other at a more distant station, a positive and a negative service-conductor for each terminal of said circuit, and a manual switch at each terminal of the lamp-circuit arranged to electrically connect said terminal with either the positive or negative service-conductor, substantially as described.

2. The combination, with a local lamp-circuit having its terminals at two different stations, of a positive and a negative service-conductor therefor at each station and of a manual switch at each station, each arranged to connect the lamp-circuit either with the positive or with the negative service-conductor, substantially as described.

3. The combination, with an electric circuit having a translating device in multiple arc with the main conductors, of a positive and a

negative service-conductor for each terminal of said circuit and of switches between each terminal of said circuit and the terminals of its respective service-conductors, substantially as described.

4. The combination, with the circuit I and its two sets of service-conductors, E F and E' F', of the switches G and H, each consisting of the case a, the spindle b, the movable spring-contact d, and the fixed half-cylindrical contacts e e and f f, eccentric to each other and to the spindle, all arranged and connected substantially as described.

JAMES F. MCELROY.
